CLAIM

The ornamental design for a cartridge for an air treatment appliance, substantially as shown and described.

DESCRIPTION

FIG. 1 is a top isometric view of a cartridge for an air treatment appliance, showing one embodiment of our new design.

FIG. 2 is a bottom isometric view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a top isometric view of a cartridge for an air treatment appliance, showing another embodiment of our new design.

FIG. 10 is a bottom isometric view thereof.

FIG. 11 is a front elevational view thereof.

FIG. 12 is a rear elevational view thereof.

FIG. 13 is a left side elevational view thereof.

FIG. 14 is a right side elevational view thereof.

FIG. 15 is a top plan view thereof; and,

FIG. 16 is a bottom plan view thereof.

The broken lines adjacent to stippled surfaces depict the claim boundaries and form no part of the claim; all other broken lines depict environment and form no part of the claim.

1 Claim, 8 Drawing Sheets
